DESIGN FOR A FOUNDATION GARMENT FOR WOMEN

Hildegard Wipperman, Chicago, Ill., assignor to The H. W. Gossard Co., Chicago, Ill., a corporation of Delaware

Application October 2, 1936, Serial No. 65,128

Term of patent 3½ years

To all whom it may concern:

Be it known that I, Hildegard Wipperman, a citizen of the United States, residing at Chicago, in the county of Cook, State of Illinois, have invented a new, original, and ornamental Design for a Foundation Garment for Women, of which the following is a specification, reference being had to the accompanying drawing forming part thereof, in which:

Fig. 1 is a front elevation of a foundation garment for women, showing my new design.

Fig. 2 is a rear elevation.

I claim:

The ornamental design for a foundation garment for women, substantially as shown.
